UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

DRILLING MECHANISM.

Application filed August 12, 1922. Serial No. 581,318.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Drill-
ing Mechanisms, of which the following is a
specification.

My invention relates to a drilling mecha-
10 nism and particularly that class of drill
which is portable and finds general use
around a mine or quarry.

One object of my invention is to produce
15 a drill of simple, efficient and economical
construction having a feeding mechanism
for driving the drill forward or backward
and by which the rate of feed may be varied
at will by wide limits while the speed of the
drill may remain constant.

20 My invention resides in the combination
of a peculiar and novel construction and re-
lation of the various parts more fully de-
scribed in this specification as set forth in
the accompanying drawings.

25 In the drawing accompanying this speci-
fication:

Figure 1 shows an exterior side view of
my device.

Fig. 2 shows an enlargement of the oper-
30 ating mechanism shown on Fig. 1.

Fig. 3 shows a face view of the feed nut
and shows the same open as is the case when
it is desired to place the nut upon the feed
shaft or to remove it from the feed shaft.

35 Fig. 4 shows an end view of Fig. 3.

In my preferred construction I employ a
hollow member 1 closed at the lower end and
pointed as indicated by the numeral 2. At
40 the lower end of the member 1 is a bracket 3
having a pointed end 4 and the fastening de-
vices 5 for securing the bracket to the hollow
member 1. The members 2 and 4 are in-
tended to engage the floor or wall of the
mine opposite to the surface which is to be
45 drilled and on account of their being pointed
they will better secure a hold upon the sur-
face to which they are applied thereby pre-
venting slippage for rotation of the mem-
ber 1. To the upper end of the member 1 is
50 secured a casing 6 having a screw threaded
engagement 7 with the upper end of the
member 1.

Within the member 1 and passing axially
through the casing 6 is a feed member 8,

exteriorly threaded as indicated by the 55
numeral 9 and provided with a longitudinal
key way or slot 10 throughout its length or
substantially its entire length. Socketed
within the casing 6 is a beveled gear 11 pro-
vided with a passage to receive the feed 60
member 8 in slidable relation thereon. Upon
the interior of the passage in the member 6
is a key 12 which engages with the slot 10 to
cause the beveled gear 11 and feed member 8
to rotate together. This construction per-
mits the feed member 8 to move up or down
65 relatively to the beveled gear 11, and to be
withdrawn without disturbing the other
parts but compels the gear and feed member
to rotate in unison. 70

Projecting from the casing 6 is a stud 13
upon which is mounted a handle gear 14 for
operating the drilling mechanism. The han-
dle 14 is provided with teeth 15 which en-
gage the teeth 16 on the beveled gear 11. A 75
washer 17 and nut 18, the latter secured to
the stud 13, maintain the handle gear in po-
sition. The rotation of the member 14 will
cause the member 6 to rotate and the mem-
ber 6 in turn will cause the member 8 to ro-
80 tate on account of the key 12 which rotates
with the member 11 and engages with the
slot 10 of the member 8.

Secured to the casing 6 is a cover mem-
ber 19 provided with an aperture through 85
which the member 8 passes and secured to
the casing 6 by means of a plurality of fas-
tening members 20. Mounted upon the cover
19 in free relation thereto, but in threaded
engagement with the feed member 8, is a 90
feed nut 21 by means of which the member 8
is caused to advance or retract when rotated.
The feed nut 21 is composed of two members
22 and 23 and hinge lugs 24 and 25 and a pin
26 passing through an aperture in each 95
hinge lug for holding the members 22 and 23
together, but permitting the latter members
to pivot relatively to each other. The feed
nut 21 being mounted upon the member 19
in free relation thereto it can be very easily 100
removed from the feed member 8 by open-
ing up the parts 22 and 23 and sliding them
away from the member 8 as indicated in
Figs. 3 and 4 and the reverse operation per-
mits of replacing the feed nut in position 105
upon the member 8. The halves of the feed
nut 21 are provided with an exterior thread
27 at one end upon which is mounted in

threaded engagement the hand wheel 28. This hand wheel serves the purpose of securing the parts 22 and 23 together and also as a means of preventing the rotation of the feed nut 21 as the feed member 8 rotates, and also as a means of rotating the feed nut in one direction, namely, opposite to that in which the member 8 rotates in the operation of drilling. This rotation of the feed nut 21 is possible on account of its detached relation to the cover 19.

To the upper end of the feed member 8 is a chuck 29 provided with an end recess 30 to receive a drill bit 31. Below the chuck 29 is a large sized washer 32 which tends to prevent the fine particles of dirt, etc., from falling directly upon the operating mechanism. The hand wheel 28 is prevented from rotating by means of the set screw 33.

20 The operation of my device is as follows:

Assuming the drill is in position for operation an operator stands in front of the handle 14, if he will rotate the handle 14 in a clockwise direction, this will cause the beveled gear to rotate and the feed member 8 in unison in a counterclockwise direction when looking downward upon the member 8. If the feed nut 21 is not held by the hand of the operator it will rotate in unison with the member 8 and in the same direction, for the reason that the friction between the member 21 and the member 8 is so arranged as to be greater than the friction between the member 21 and the member 19. If the member 21 rotates at the same speed as the member 8 and in the same direction the member 8 will not move in or out of the casing 1.

If the member 28, however, is grasped by the hand of the operator while he still rotates the handle 14 in a clockwise direction, the member 21 being held stationary and the member 8 rotating relative thereto, the member 8 will be caused to advance or move outwardly from the casing 1, the rate of advance relative to the rate of rotation of the member 8 being determined by the pitch of the thread on the members 8 and 21. If, however, the operator should rotate the member 21 in a counter-clockwise direction (when looking down upon the member 28) and at the same time rotate the member 14 in a clockwise direction the rate of feed of the member 8 or the rate at which it will advance will be increased over that described in the last paragraph.

Likewise, if the rotation of the member 21, on account of its friction with the rotating member 8, is retarded by means of allowing the hand wheel 28 to slide through the hand of the operator while the member 14 is still rotated as already described, the rate of advance or feed of the member 8 will be less than if the member 21 were held stationary and will be somewhat greater

than if the member 21 were allowed to rotate with the member 8 and at the speed of the member 8.

It will be seen from this construction that the feeding mechanism has a wide range of feed control from the zero rate, in either direction, depending upon the rate at and the direction in which the feed nut 21 is rotated relative to the feed member 8 as already described.

75 The operator can also produce a negative rate of speed, that is, to cause the member 8 to be withdrawn within the member 1 while the handle 14 is being rotated if he but rotates the hand wheel 28 at a sufficient rate in a counterclockwise direction (when looking downward upon the hand wheel). This is true when he is able to rotate the hand wheel 28 in a counterclockwise direction at a rate of speed greater than that of the member 8.

80 It will be quite apparent that there are many modifications which may be made in the construction as disclosed and described herein without departing from my invention, and that the mechanism is suitable for motor operation, as well as hand operation. This wide variation in the rate of feed will be found particularly advantageous around a mine where material is to be drilled of 90 various degrees of hardness.

95 I claim:

1. A drilling mechanism having in combination a support, a feed member arranged to operate a drill bit, mechanism for rotating the feed member, a feed nut mounted upon the feed member and having a threaded engagement therewith and rotatable relative thereto and having free longitudinal movement in one direction.

100 2. A drilling mechanism having in combination a support, a feed member arranged to operate a drill bit, mechanism for rotating the feed member, means threadably mounted upon the feed member and rotatable therewith and movable longitudinally therewith in one direction to advance or retract the feed member at will without changing the direction of rotation of the feed member.

110 3. A drilling mechanism comprising in combination a support, a feed mechanism provided with an external thread and arranged to operate a drill bit, operating mechanism for rotating the feed mechanism, means on the operating mechanism engaging with means on the feed member to cause the two to rotate in unison, but permit the said means to simultaneously slide forward and back relative to each other, a quick detachable feed nut comprising two parts forming a collar and having an internal thread to engage with the thread on the feed mechanism and rotatable about the axis of the feed mechanism and movable in one longitudinal direction together with the feed

115

120

125

130

- mechanism and a member mounted on the feed nut to hold the parts together on the feed mechanism and to control the rotation of the feed nut relative to the feed mechanism, the said collar operating to move the feed member forward when it rotates in the direction of rotation as the feed member but at a less speed and to prevent the feed member moving forward when the collar rotates in the same direction and at the same speed as the feed member and to move the feed member back when the collar rotates in the opposite direction to that of the feed bar.
4. A drilling mechanism having in combination a support, a feed member arranged to operate a drill bit, mechanism for operating the feed mechanism, a quick attachable and detachable split feed nut having means to hinge its parts together mounted on the feed mechanism and movable relative to the support in one longitudinal direction, means to hold the parts of the feed nut together and control the rotation of the feed nut relative to the feed mechanism for varying the rate of longitudinal movement of the feed member when drilling.
5. A drilling mechanism comprising in combination a tubular support, an elongated feed member provided with a longitudinally disposed slot and an external thread substantially the entire length and mounted to be advanced or retracted within the tubular support, a gear provided with a key engaging the slot in the feed member, manually operated means engaging with the gear to rotate the gear, means on the feed member to receive a drill bit, a feed nut for moving the feed member forward or back when the feed member is rotated, the feed nut comprising a two part hinged collar threaded internally and engaging the thread on the feed member and free to be rotated by the feed member in the same direction or to be rotated manually in either direction about the axis of the feed member to vary the forward or back movement of the feed member and means to hold the parts of the feed nut in position upon the feed member and means on the end of the tubular member to engage a support opposite the point where the drill is to operate such that the point of the drill bit and point of support of the drilling mechanism will be at substantially opposite ends of the longitudinal axis of the tubular and the feed member.
6. A drilling mechanism comprising in combination a tubular support, an elongated feed member provided with a longitudinally disposed slot and an external thread substantially the entire length positioned in telescopic relation to the support, a gear provided with a key engaging the slot in the feed member, manually operated means
- engaging with the gear to rotate the gear, means on the feed member to receive a drill bit, a feed nut for moving the feed member forward or back within the tubular support when the feed member is rotated, the feed nut comprising a two part collar threaded internally to engage the thread on the feed member and free to rotate about the axis of the feed member and means to hold the parts of the feed nut in position upon the feed member and means slidably mounted on the tubular support to engage a solid support to brace the drilling mechanism and to prevent the rotation of the mechanism while drilling.
7. A drilling mechanism comprising in combination a tubular support, an elongated feed member provided with an external thread substantially its entire length and positioned in telescopic relation to the support, operating mechanism for rotating the feed member, means on the operating mechanism engaging with means on the feed mechanism to cause the two to rotate in unison but permit the feed member to simultaneously move forward and back relative to the operating mechanism, a collar having a threaded engagement with the thread on the feed member to effect the forward movement of the feed member upon relative rotation of the feed member and collar and means to rotate the collar in one direction to retard the forward movement of the feed member and to rotate the collar in the opposite direction to assist the forward movement of the feed member.
8. A drilling mechanism comprising in combination a support and a threaded feed member having a common axis, the feed member having a drill to engage the body to be drilled and means on the support to engage an oppositely disposed body to act as a brace, threaded means rotatably mounted on the feed member and movable longitudinally of the support away from the support and adapted to control the longitudinal movement of the feed member relative to the support and means mounted on the support to operate the feed member.
9. A drilling mechanism comprising in combination two telescopic members having a common axis, means on one member to engage a fixed support and means on the other member to receive a drill, the two means being substantially at opposite ends of the said axis, and means to rotate the said member relative to each other and means to move the members longitudinally of each other and at varying speeds as desired by operator.
- In testimony whereof I affix my signature.
- HOMER P. CHANDLER.
